UNITED STATES PATENT OFFICE.

FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

REGISTERING MECHANISM.

Application filed August 20, 1921. Serial No. 493,964.

To all whom it may concern:

Be it known that I, FARNUM F. DORSEY, a citizen of the United States, residing at Rochester, in the county of Monroe and State of New York, have invented certain new and useful Improvements in Registering Mechanisms; and I do hereby declare the following to be a full, clear, and exact description of the invention, such as will enable others skilled in the art to which it appertains, to make and use the same.

This invention relates to instruments in which rotations or other movements are registered by a train of rotary number-wheels.

15 The invention is particularly applicable to odometers, but may be useful in connection with instruments for various other purposes.

20 The object of the invention is to provide an instrument, of the type in question, with improved means for resetting the number-wheels either to zero or to any desired number within their scope. In some previous instruments of the type in question it has been customary to provide resetting means 25 by which the wheels may all be quickly reset to zero by movement in one direction, but in such instruments there has been no provision for setting the wheels to any other number. In other instruments it has been 30 customary to provide resetting means by which the wheel of lowest denomination may be turned in either direction, the other wheels being moved in train by the action of the usual transfer mechanism. In such 35 instruments the wheels may be set to any desired number, but the operation is comparatively slow and laborious.

In accordance with the present invention, 40 resetting means are provided by which motion in one direction results in quickly aligning the similar digits on the number-wheels and turning the wheels simultaneously to zero or to any number in which the digits are all similar, and by which rotation in the 45 opposite direction may be imparted to the wheel of lowest denomination and from this wheel to the others in train. By the combination of these two modes of motion the wheels may be quickly reset to any desired 50 number.

Other objects and features of the invention will be set forth hereinafter, in connection with the description of the illustrated embodiment of the invention.

55 In the accompanying drawings, Fig. 1 is

a vertical sectional view of odometer mechanism embodying the present invention, approximately on the line 1-1 in Fig. 2. Fig. 2 is a horizontal section, approximately on the line 2-2 in Fig. 1. Fig. 3 is a vertical section of the number wheels and their supporting and actuating means, approximately on the line 3-3 in Fig. 2. Fig. 4 is a side-elevation showing certain details of the resetting-mechanism. Fig. 5 is a front-elevation of two adjacent number-wheels, partly in section. Fig. 6 is a perspective view of one of the pawl-springs for aligning the number-wheels.

The invention is illustrated as embodied 70 in an odometer such as is used for registering the distance travelled by a vehicle, and only so much of the instrument is shown as is necessary for an understanding of the invention. The instrument is provided, as 75 usual, with two sets, 10 and 11, of number-wheels, the set 10 being used to register the total distance travelled, while the wheels 11 constitute means for registering trips. Only 80 the latter set is arranged to be reset.

The odometer is driven by a vertical worm 12, which is connected in any suitable manner with the mechanism of the vehicle. This worm is journalled in the frame 13 of the instrument, and the frame and the mechanism are enclosed in a metal casing 14, of which only portions are shown. The front of the casing is provided with openings covered with sheets 15 of transparent material, through which the number-wheels are 90 visible.

The means for supporting and driving the wheels 10 are immaterial to the present invention and are not shown. The wheels 11 are in the form of rings, arranged to turn 95 on a stationary drum 16, which is hollow throughout most of its length but is provided with an integral closed head 17 and a removable head or plate 18 at the opposite end. These heads are perforated to receive 100 a central shaft 19, which serves as a support for the drum, the shaft being journalled in the frame 13.

The number-wheels are rotated through the agency of epicycloidal gearing comprising a gear-wheel 20 which meshes with the worm 12. The wheel 20 bears and rotates upon two central gears 21 and 22, and it also constitutes a carrier for two planetary pinions 23, which mesh with the gears 21 and 110

22 and turn freely in recesses in the carrier. The gears 21 and 22, altho of the same diameter, have different numbers of teeth, so that each revolution of the pinions 23 around 5 the gears results in a slight differential rotation of the gears.

By means of a sleeve 24 the gear 22 is fixed to the head 17 of the drum 16 and also to a plate 25, and the several parts so connected 10 are held against relative rotation by a pin 26. The plate 25 engages a suitable abutment on or opening in the frame 13, being thereby held against rotation, so that the drum 16 and the gear 22 are stationary, tho 15 supported on the rotatable shaft 19.

The gear 21 is fastened to the shaft 19 by a pin 28, and is thus also secured to a sleeve 27 by which it is connected with mechanism for actuating the wheels 10. This mechanism may be of any usual or suitable form 20 and is therefore not fully shown nor described. Since the gear 22 is held against rotation, the effect of the epicycloidal gearing is imparted wholly to the gear 21, from 25 which it is transmitted, through the shaft 19, to the initial wheel of the series 11.

The epicycloidal drive-mechanism constitutes no part of the present invention, and is therefore not claimed herein.

30 For the convenience in manufacture the number-wheels 11 are all made exactly similar in form. Each wheel is provided, on one side, with a continuous set of internal gear-teeth 29 (Fig. 4) and on the opposite side with two teeth 30 (Fig. 3). Motion is transferred from each wheel to the next by a transfer-pinion 31, these pinions being mounted to turn freely on a shaft 32 mounted in the heads of the drum 16. At 35 each complete rotation of the number-wheels (except that of the highest denomination,) the two teeth 30 on the one wheel impart a partial rotation to the corresponding pinion 31, and this pinion transmits the motion 40 to the teeth 29 of the adjacent number-wheel, thus causing one-tenth of a rotation 45 of the latter.

The pinion 31 and the number-wheels are 50 normally held against rotation by yielding spring-pressed detents in the form of plates 33, which slide vertically between spacers 55 33 in the interior of the drum 16 and are pressed upwardly by springs 34. The forked upper end of each plate 33 bears against two teeth of the pinion 31 and tends to 60 prevent rotation of the latter, and also to insure that it shall normally move to and remain in a position suitable for engagement with the two teeth 30 by which it is actuated. When the pinion is so actuated, however, the detent-plate yields downwardly to permit the pinion to rotate.

The novel construction just described is 65 particularly useful in connection with resetting-mechanism of the type herein de-

scribed, but it may also be used in registering-mechanisms without provision for resetting or with resetting devices of other or ordinary form.

To permit resetting in the manner characteristic of the present invention, the first wheel of the train 11 is connected with the shaft 19 through a friction-clutch shown in Figs. 2 and 4. A drum 35 is pinned on the shaft and is embraced by a helical spring 36 having outwardly-bent ends. During normal operation the end 37 engages a shoulder 38 on a member 39 which is attached to the primary number-wheel 11, so that the clockwise rotation of the shaft (as seen in Fig. 4) causes the spring, through its frictional engagement with the drum 35, to drive the number-wheel. Any resistance of the wheel to such motion causes the spring to clasp the drum the more tightly, so that the friction is always sufficient for the purpose.

The member 39 may be punched from sheet-metal, in a form to fit closely in the recess within the gear-teeth 29 on the primary number-wheel, and it is provided with three teeth 40 which engage spaces between the teeth 29. This arrangement provides the primary wheel with the abutments or shoulders necessary for cooperation with the spring 36, and permits the use of a primary wheel similar in all respects to the other number-wheels, the gear-teeth 29 serving, in this instance, merely to provide a means of connection with the member 39.

100 The resetting mechanism characteristic of the present invention comprises a recessed wheel 41 which turns loosely on the drum 35 and overhangs the clutch-spring 36. A pin 42 is fixed in the wheel 41 in position to be interposed between the ends of the clutch-spring. A thumb-wheel 43, journalled or a stud 44 on the frame of the instrument, is provided with gear-teeth which mesh with teeth on the resetting-wheel 41. The thumb-wheel projects through a slot or opening in the front of the casing 14, so that it may be rotated manually in either direction, the gear-teeth providing a roughened surface 105 convenient for the purpose.

110 When the resetting-wheel is rotated in a clock-wise direction the pin 42 presses the end 37 of the clutch-spring against the shoulder 38 and thus drives the primary number-wheel in the normal direction, the motion being transmitted to the other number-wheels through the transfer-pinions, so that in this way the odometer may be set or advanced unit-by-unit. Since the clutch drum 35 cannot participate in this movement the clutch-spring slides upon it, the resistance due to this cause being slight owing to the fact that it is in a direction to uncoil the spring.

115 When the resetting-wheel is turned coun-

ter-clockwise, the pin 42 engages the other end 45 of the clutch-spring and presses it against a second shoulder 46 on the member 39, thus rotating this member and the primary number-wheel in a reverse or counter-clockwise direction, the clutch-spring sliding on the drum as before. In order that this reverse rotation may act to align the number-wheels and to rotate them all simultaneously, means are provided for interconnecting the wheels independently of the transfer-pinions. For this purpose each wheel is provided, on each of its side-faces, with a channel 47, of which the depth is graduated so as to provide, at one point, an abrupt shoulder 48, these shoulders facing in opposite directions on opposite sides of the wheel. The channels in the meeting faces of adjacent wheels form a closed annular recess, and in each such recess is enclosed a split ring 49 of spring-metal, the ends of which are bent apart laterally so that they tend to spring into the deeper parts of the channels and engage the shoulders 48, as shown in Fig. 5. During rotation of the number-wheels in the normal direction the pawl-springs 49 merely snap idly over the shoulders, but when the wheels are rotated reversely by the resetting-mechanism the springs engage the shoulders positively, and thus transmit rotation in unison from each wheel to the next, while also aligning the wheels with similar digits in line.

To reset the wheels to zero it is necessary merely to turn them backward until the aligned zeros come into view, an operation which requires, in no case, more turns than the number of number-wheels in train. To reset the wheels to any required number, it is preferable to turn the wheels backwardly until the aligned digits show the number next below that required, and then turn the resetting mechanism forwardly until the necessary number of units have been added. Thus, for example, if the number 843 were desired, the mechanism would be turned backwardly to align the digits and bring the number 777 into view, and then forwardly to 843.

The invention is not limited to the embodiment thereof hereinbefore described and illustrated in the drawings, but it may be embodied in various other forms within the scope of the following claims.

The invention claimed is:

1. Registering-mechanism comprising: a coaxial train of number-wheels; transfer-gearing, interconnecting the wheels and adapted to cause serial movement thereof in a forward direction, and yieldable to permit rotation of the wheels independently of the operation of the gearing; manually operable means for rotating the initial wheel in either direction to reset the mechanism; and ratch-

et-connections, between each pair of adjacent wheels, arranged to communicate reverse rotation from each wheel directly to the next higher wheel in series.

2. Registering-mechanism comprising: a coaxial train of number-wheels; transfer-gearing, interconnecting the wheels and adapted to cause serial movement thereof in a forward direction, and yieldable to permit rotation of the wheels independently of the operation of the gearing; ratchet-connections, between each adjacent pair of wheels, arranged to permit each wheel to overrun the next higher wheel, but to prevent reverse relative rotation; and manually-operable resetting means operative, through the transfer-gearing, to reset the wheels serially, and operative, through the ratchet-connections, to reset the wheels simultaneously.

3. Registering-mechanism comprising: a train of number-wheels; a rotary resetting-member; and connections, between the number-wheels and the resetting-member, whereby rotation of the resetting-member in one direction resets the number-wheels serially and rotation of the resetting-member in the opposite direction resets the number-wheels simultaneously.

4. Registering-mechanism comprising: a train of number-wheels; a manually-operable resetting-member; and connections between the number-wheels and the resetting-member whereby the number-wheels may be reset in series or simultaneously at will.

5. Registering-mechanism comprising: a train of number-wheels; a manually-operable resetting-member; and connections between the number-wheels and the resetting-member whereby the number-wheels may be rotated in series in one direction, and simultaneously in the opposite direction.

6. Registering-mechanism comprising: a train of number-wheels; ratchet-connections between the wheels for causing them to rotate simultaneously when one of the terminal wheels of the train is rotated in a given direction; and resetting-means for so rotating said terminal wheel and for alternatively rotating the primary wheel in a direction to cause rotation of the wheels in series.

7. Registering-mechanism comprising: a train of number-wheels provided with recesses in their adjacent faces, said recesses being provided with oppositely-directed shoulders; and spring-pawls in the recesses cooperating with said shoulders to cause simultaneous rotation of the wheels in one direction of movement.

8. Registering-mechanism comprising: a train of number-wheels provided with annular recesses in their adjacent faces, said recesses being provided with oppositely directed shoulders; and spring-pawls located in the recesses and cooperating with said

shoulders therein, each pawl having the form of a resilient split ring.

9. Registering-mechanism comprising: a cylindrical support; a series of annular number-wheels mounted and rotatable thereon, each wheel being provided with internal gear-teeth on both sides and with annular recesses in its lateral faces outside said gear-teeth; transfer-pinions mounted on said support within the number-wheels and cooperating with the gear-teeth thereon; and spring-pawls located in said recesses and operable to limit relative rotation of the number-wheels in one direction.

10. Registering-mechanism comprising: a train of coaxial number-wheels having number-bearing rims; ratchet-connections, between adjacent faces of the wheels, located near their said rims and arranged to permit each wheel to overrun the next adjacent higher wheel but to prevent reverse relative rotation; transfer-gearing, located within the peripheries of the wheels and within the paths of movement of said ratchet-connections; and manually-operable means for rotating a terminal wheel of the series to reset the number-wheels.

FARNUM F. DORSEY.
